CLAIM

The ornamental design for a surgical robot, as shown and described.

DESCRIPTION

FIG. 1 is a top, rear, left-side isometric view of an embodiment of the surgical robot, showing our new design; FIG. 2 is a rear, right-side isometric view thereof; FIG. 3 is a front, left-side isometric view thereof; FIG. 4 is a front elevation view thereof; FIG. 5 is a top plan view thereof; FIG. 6 is a right-side elevation view thereof; and, FIG. 7 is a rear elevation view thereof.

The broken line portion of the figure drawings is included to show unclaimed subject matter only and forms no part of the claimed design.
